UNITED STATES PATENT OFFICE.

ROBERT A. OGLE, OF CHICAGO, ILLINOIS.

MATERIAL-HANDLING APPARATUS.

1,112,084.

Specification of Letters Patent. Patented Sept. 29, 1914.

Application filed December 4, 1911. Serial No. 663,896.

To all whom it may concern:

Be it known that I, ROBERT A. OGLE, a citizen of the United States, residing at Chicago, in the county of Cook and State of Illinois, have invented a new and useful Improvement in Material-Handling Apparatus, of which the following is a specification.

My invention relates, more particularly, to apparatus for transferring coal, or the like, from a hopper at one level to a bin above the hopper; and my object, generally stated, is to improve upon prior structures of this character, to the end of rendering them better adapted for performing their functions.

Referring to the accompanying drawings—Figure 1 is a broken view in elevation of apparatus constructed in accordance with my invention, portions of the structure therein shown being illustrated in section, one of the loader-devices for controlling the discharge of the material from the hopper being shown in the position it assumes when in position for receiving a charge from the hopper, and the other loader-device illustrated being shown in the position it assumes when in position for discharging a measured quantity of material into its co-operating elevating bucket. Fig. 2 is a broken view in vertical sectional elevation taken through the hopper and loader mechanism proper, showing the loader-mechanism in position for discharging into its co-operating bucket. Fig. 3 is a broken section taken at the line 3 on Fig. 4 and viewed in the direction of the arrow. Fig. 4 is a view like Fig. 2, showing the loader-mechanism in the position it assumes while being filled from the hopper. Fig. 5 is an enlarged broken view in side elevation of a detail of the connection between the pivoted door and gate of the loader-mechanism. Fig. 6 is a broken view in front elevation of the structure shown in Fig. 5, this view being taken at a line corresponding with the line 6 on Fig. 5 and viewed in the direction of the arrow. Fig. 7 is an enlarged sectional view taken at the line 7 on Fig. 1 and viewed in the direction of the arrow. Fig. 8 is a section taken at the line 8 on Fig. 9 and viewed in the direction of the arrow, the section being taken through one of the elevating buckets. Fig. 9 is a sectional view in side elevation of the construction shown in Fig. 8, the bucket in this view being represented in the position it assumes while being filled

from its co-operating loader-mechanism, the section being taken at the line 9 on Fig. 8 and viewed in the direction of the arrow; and Fig. 10, a view similar to Fig. 9, showing a modification of the connections between the bucket and its bail, when the bucket is to be filled from the side opposite to that from which it is filled in the construction illustrated in Fig. 1.

I have devised my invention for use, more particularly, in elevating coal from a hopper into which it is discharged from cars on a track, to a bin or bins above the level of the track from which it may be removed periodically, or otherwise, as required, such as for instance to load tenders of locomotives, and in its preferred form it involves, generally stated, the employment of two co-operating loader-mechanisms adapted to alternately discharge material, received from the hoppers, into hoisting buckets operating in opposite directions to elevate the material in predetermined amounts to the bin or bins, though it will be understood from the following description that certain features of my invention may be utilized in apparatus in which but a single elevating bucket is employed.

Referring particularly to Figs. 1 to 9 inclusive, a pair of pits, usually provided in apparatus of this kind, is represented at 11, these pits being located underground in the arrangement illustrated, adjacent side walls of which are represented at 12. Located above and between these pits is a hopper 13 which is usually located beneath the ground, and into which the cars (not shown) loaded with the material to be hoisted, discharges. The bottom of the hopper 13 is formed of two downwardly-converging sections 14 and two upwardly-converging intermediate sections 15. The lower end-portions of the sections 14 are provided with openings 16 which form discharge-openings at opposite sides of the hopper for the material periodically withdrawn therefrom in a manner herein-after described, these discharge-openings preferably being flanked by plates 17 having curved outer edges 18. Located below and registering with each of the discharge-openings 16 is an inclined chute 19 having a bottom-plate 20 which is formed with a curved section 21 at its upper end at which it connects with the hopper 13, the plate 20 resting on supports 22 in the pit and secured thereto in any desired manner to be rigid.

therewith. Extending across the front end of each chute 19 and above the bottom-plate 20 is a plate 23 which latter, in connection with the side walls 24 of the chute and the bottom-plate 20 thereof, forms a discharge-opening 25 at the lower front end of the chute. Each of the chutes 19 contains a gate 26, and coöperating with each of the discharge-openings 25 is an outwardly-opening door 27, preferably in the form of an apron, pivoted to the respective chutes 19 as hereinafter described. Each gate 26 is formed of a pair of segmental side plates 28 and a curved connecting plate 29 therefor, which latter forms the gate-proper, each gate being of a height substantially equal to the height of the discharge-opening 16 and describing an arc of substantially the same radius as the curved edges 18 of the plates 17. The gates 26 are fixed at their plates 28 on trunnions 30 pivoted on and extending through the side walls 24 of the respective chutes 19, the axes upon which these trunnions rotate being the center of the arcs described by the curved surfaces 18 of the plates 17. The aprons 27 are formed of front plates 31 and rearwardly-extending plates 32 connected thereto, the plates 32 extending beyond the chute-walls 24 at opposite sides of the respective chutes 19, the aprons 27 being pivoted as indicated at 33 to the lower end of the adjacent bottom-plates 20 as represented in Fig. 4, whereby the aprons 27 may be swung upon their pivots 33 to open or close the discharge-outlets 25 of the chutes 19 as described, the plates 31, when the aprons 27 are in the position illustrated of the one shown in Fig. 4, serving to prevent the discharge of material from the chutes 19, and when swung downwardly on their pivots 33 to the position illustrated in Fig. 2, serving to direct the material, discharged from the loaders, into buckets hereinafter described.

In the construction illustrated, it is intended that the movable aprons 27 be operated with their respective gates 26 for causing the aprons 27 to be swung downwardly to open condition in the movement of their respective gates to a position in which they close the hopper-outlets 16, and be moved to closed condition in the movement of their coöperating gates 26 to a position in which the hopper-outlets 16 are opened, and to effect the simultaneous operation of the aprons 27 and gates 26 as described, I provide the following described mechanisms: Secured to the side-plates 28 of the gates 26 are bars 34 which are connected, through the medium of a rod 35, with the rear ends of links 36, the forward ends of which links are pivotally connected with levers 37 between the ends of the latter by means of rods 38; the levers 37 being fixed on the outer ends of the trunnions 30 beyond the sides of the chutes 19. The aprons 27 are connected with their

coöperating gates 26 through the medium of link-mechanisms located beyond the sides of the chutes 19 and aprons 27, and comprising, in their preferred form, links 39 pivotally connected at 35 with the upper ends of the bars 34 and carrying pins 40 in their lower ends, and links 41 pivotally connected at their lower ends as indicated at 42 to the sides 32 of the movable aprons 27 at opposite sides thereof at a distance from the pivot 33 less than the distance from the pivot 30 to the point 35, and containing elongated slots 43 in their upper ends through which the pins 40 extend, and through the medium of which pins the links 39 and 41 are pivotally connected together by a slide connection. The lower ends of the links 39 are shouldered as represented at 44, these shoulders fitting against stops, shown as cross-pins 45, carried by the links 41 when the links 39 and 41 are in alining position, as represented in Fig. 4. The arrangement of the parts described is such as to cause the gates 26 to be open when the aprons 27 are in position for closing the chute-outlets 25, and in this position of the gates 26 and aprons 27 the axes upon which the trunnions 30 rotate are slightly out of line with the pivots 35 and 42, as represented in Fig. 4, though it is within my invention to so arrange the lever-mechanism that the trunnion axes and pivots 35 and 42 will be in alinement.

It will be understood from the foregoing that when the hopper 13 contains material such as coal, this material, when a loader-mechanism is in the position illustrated in Fig. 4, will flow into the chute 19, the escape therefrom being prevented by its coöperating apron 27, and when the levers 37 are rocked downwardly, the gate 26 will be swung upwardly to shut off the flow of coal from the hopper, and the apron 27 swung downwardly to permit the charge in the chute 19 to discharge into a coöperating hoisting-bucket hereinafter described. Swinging the levers 37 upwardly to the position illustrated in Fig. 4 will cause the gate 26 and apron 27 connected therewith to be simultaneously moved to the position illustrated in Fig. 4, namely wherein the gate is withdrawn from registration with the hopper-outlet 16 and the movable apron 27 affords a closure for the lower end of the chute 19.

Pairs of guides extending upwardly from the bottom of the pits 11 are represented at 46, these guides, in practice, extending to a point closely adjacent to the receiving-bin or bins (not shown) and serving as guides for hoisting buckets, one of which is illustrated at 47 for periodically receiving material from the hopper-bin 13 through the medium of a loader-mechanism described. In the construction illustrated, the buckets 47, operating in the guides 46, are intended

to be operated simultaneously, but in opposite directions, by hoisting mechanism (not shown), including a cable 47^a, in accordance with common practice, the arrangement of 5 the hoisting mechanism and buckets being such as to cause one of the buckets 47 to be at the bottom of the pit 11 into which it extends when the other bucket is at the top of its respective guide 46. Thus considering 10 the mechanism shown in Fig. 1, the bucket 47 therein shown would be at the bottom of the pit 11 into which it extends, whereas the bucket operating in the guides 46 at the other side of this figure would be at the 15 height of its upward travel, in which position, in practice, it would be raised sufficiently far to permit its contents to be dumped therefrom into a bin.

The coöperating gates 26 and aprons 27 20 are designed to be automatically operated by the movements of the buckets 47, and to effect this, in the preferred illustrated construction, I provide cross-bars 48 which are guided at their opposite ends between the 25 guides 46 and guide-members 49, these cross- rods being connected at their opposite ends with rods 50 which latter are connected at their upper ends with connectors 51 pivoted to the outer ends of the levers 37, the cross- 30 rods 48 extending into the path of downward movement of the respective buckets 47 and the connections between these cross- rods and levers 37 being such as to cause the 35 respective gates 26 and aprons 27 operated thereby to extend into the position represented in Fig. 2 when their coöperating buckets reach the limit of their downward movements, as hereinafter described. The 40 lever-mechanisms connecting together the respective gates and movable chutes of the loading devices are connected together by means of a cable 52 provided at opposite 45 ends with yokes 53 which latter are pivotally connected with the bars 38, the cable 52 passing over pulleys 54 which, in practice, 50 would be secured to the super-structure above the hopper 13.

Assuming the parts of the apparatus to be in the relative positions illustrated in 55 Fig. 1, operation of the hoisting mechanism hereinbefore referred to for operating the buckets 47 will cause the bucket 47 illustrated in Fig. 1 to ascend and the companion bucket 47 operating in the guides 46 at the 60 left-hand side of this figure, to descend. Lowering of the last-referred to bucket causes it to bear down upon the bar 48 below it, with the result of drawing down the rods 50 connected therewith, thereby operating the lever-mechanism connecting together the gate 26 and movable apron 27 of the 65 loader mechanism at the left-hand side of Fig. 1 and causing said gate and movable apron to be moved to the positions illustrated in Fig. 2. Thus operating the loader-

mechanism causes a measured charge of material to be dumped into its coöperating bucket 47, the gate 26 of this loader-mechanism simultaneously therewith shutting off the further flow of coal from the hopper to 70 the chute 19. The loader-mechanism, thus operated to discharge into its coöperating bucket 47, remains in discharging position until the cross-bar 48 coöperating with the other bucket 47 is engaged by the descending 75 bucket for coöperating with this last referred to bucket to dump a charge into the latter. When this last referred to operation takes place, the loader-mechanism which was previously operated as stated, is operated to cause its apron 27 and gate 26 to be moved to the positions illustrated in Fig. 4, through the medium of the cable 52, this cable connection between the compound 80 lever connections for the gates 26 and movable aprons 27 operating to automatically cause one of said lever-mechanisms to be raised and the parts controlled thereby actuated, when the other of said compound lever-mechanisms is lowered.

By the preferred construction illustrated, the buckets 47 are caused to be projected beneath the outer ends of the movable aprons 27, when the latter are in the position of the one illustrated in Fig. 2, in order 95 that all the material, discharged from the chute 19 through its movable apron 27 as hereinbefore described, shall enter the bucket and to effect this operation I construct the mechanism as illustrated and of 100 which the following is a description: The buckets 47 are provided with bails 55 to which the hoisting cable 47^a is connected at the opposite ends of the latter, each bail being provided with shoes 55^a which slide 105 in the coöperating guides 46, and carrying at its lower end heads 56 which extend below the respective bucket at opposite sides thereof. The buckets 47 are pivotally secured to their respective bails 55 through 110 the medium of shafts 57 located at one side of the guides 46 as represented of the construction in Figs. 1 and 9, these shafts being journaled in bearings 58 on the under sides of the buckets and in opposed heads 56 of 115 the bails. The bail-heads 56 at the sides of the guides 46, opposite to that at which the shafts 57 are journaled, are provided with cross-bars 59 upon which the respective buckets rest in the operation of raising 120 and lowering them. At the bottom of each pit 11 is a pair of supports 60 which are spaced apart and upon which the buckets 47 are adapted to seat when at the limit of 125 their downward movement, the supports 60, in Fig. 1, nearest the loader-mechanism, being of slightly less height than the other supports 60. When a bucket 47 nears the limit of its downward movement, the support 60 to the right in Fig. 9 will be first 130

engaged by the bottom of the bucket, with the result of tipping the latter, at its upper end, to the left in Fig. 9 the bucket turning on the shaft 57 and finally seating on both 5 of the supports 60 beneath it in an inclined position as represented in Figs. 1 and 9, wherein it is projected at its upper open- 10 end a slight distance beneath the apron 27 coöperating therewith. In the operation of raising the bucket 47 from the position illustrated in Figs. 1 and 9, the bucket is first raised from the support 60 at the left-hand side of Fig. 9, the bucket, rotating on its shaft 57 until this bucket engages with the 15 shaft 59, by this operation the bucket being withdrawn from a position in which it extends under the apron 27 coöperating therewith, and may be lifted without disturbing the position of the loader-mechanism.

20 By the arrangement of the connection between the gate and door above described for the gates 26 and aprons 27, it will be readily understood that when the levers 37 are swung downwardly from the position illustrated in Fig. 4 to the position illustrated in Fig. 2, the gate 26, in its initial upward movement, will move at a much greater speed than the speed at which the apron 27 swings downwardly in the initial movement of the latter, and the apron 27 in its final downward movement will move at a greater speed than the speed at which the coöperating gate 26 travels in its final closing movement, and thus the gate 26 is 25 moved to a position in which it substantially cuts off the flow of coal from the hopper 13 to the chute 19 before the coal begins to discharge from said chute over the apron 27. The gate 26, however, is caused to move 30 through running coal when swung upwardly, as stated, by reason of the displacement of the coal in the chute 19 caused by the lowering of the apron 27 in its initial movement, supplemented by the action of 35 the gate 26, the gate-proper 29 of which by being preferably spaced from the curved portion 21 of the chute-bottom 20 operating as it swings upwardly to open to the coal in the chute 19 the space between the plate 40 29 and bottom 21, thus, in effect, progressively enlarging the coal-filling space afforded in the chute 19 as the gate 26 swings upwardly, it being preferred that the chute-sections 21 and the plates 29 be of such con- 45 tour and so arranged that the spaces between these parts become gradually shallower from front to rear when the gates 26 are in open condition as represented in Fig. 4, in the construction illustrated this 50 arrangement being effected by forming the plates 21 and 29 of arc-shape and arranging them in non-concentric relation, the plates 29 being movable adjacent to the upper ends of the coöperating plates 21 in close prox- 55 imity thereto so as to prevent lumps of coal 60 from becoming wedged between the plates 21 and 29. In the act of swinging the gate 26 and movable apron 27 back to the position illustrated in Fig. 4, the apron 27 in its initial upward movement closes very rap- 70 idly as compared with the lowering of the gate 26, the apron 27 swinging to a position in which the outlet 25 of the chute 19 is effectually closed against egress of coal therefrom before the gate 26 has opened 75 sufficiently far to permit coal to flow into the chute 19 from the hopper 13.

By positioning the gate and chute lever-mechanism as described, the force exerted by the coal against the plate 31 exerts practically no tendency to actuate these lever-mechanisms from the position illustrated in Fig. 4, as the crank-connections between the gate 26 and the movable apron 27 and comprising the bars 34 and links 39 and 41, 80 are substantially on dead center, and the force exerted by the coal lying upon the plate 29 is sufficient to overcome the leverage exerted by the links 39 by reason of the pressure of coal against the plate 31. 85

In the movement of the loader-mechanisms to discharging position represented in Fig. 2, lugs 27^a on the sides of the aprons 27 are engaged by the links 41, causing the links 39 and 41 to swing forwardly and disengage the shouldered portions 44 of the links 39 from the pins 45 as illustrated in Fig. 2, this feature of the construction being provided for the purpose of permitting the aprons 27 to swing upwardly without 90 operating their coöperating gates 26 should the apparatus become clogged in such a way as to cause the coöperating buckets 47 to exert, in their upward movement, lifting action on the aprons 27, it being understood 100 that the feature just referred to of the construction is provided for the purpose of preventing damage of the apparatus or unintended discharge of coal through said chutes 105 110 in case the buckets 47 in their upward movements exert lifting force on the aprons 27.

The construction illustrated in Fig. 10 shows a modification of the means for tilting the bucket 47 toward the loader-mechanism when the arrangement of the hopper 13 and the receiving-bin or bins to be supplied therefrom occupy such positions, as they sometimes do in practice, as to render it necessary that the buckets 47 be filled 115 from the side opposite to that illustrated of the one on the right-hand side in Figs. 1, 2 and 4. In the case of this modification, the supports upon which the bucket 47 would rest and which supports are represented at 120 125 130 61, are of unequal height as described of the supports 60, but are transposed relative thereto, as illustrated in Fig. 10, to cause the bucket 47 to tilt to the right in Fig. 10 to position its side wall at the right-hand 135

side of this figure, below the movable apron 27 of the loader-mechanism, which would, in this case, be located to the right of the bucket in Fig. 10. The connections between 5 the bail 55 and its coöperating bucket 47 are the same in this modified construction as those of the construction illustrated in Fig. 9, excepting that in the construction illustrated in Fig. 10, the shaft 57 is located in 10 vertically elongated slots 62 in the bail-heads 56 of the bail 55. In the lowering movement of the bucket, the latter is supported on the bail 55 at the shafts 57 and 59, the shaft 57 resting in the lower ends of 15 the slots 62. As the bucket nears the limit of its downward movement, it will first engage with the support 61 at the left-hand side of Fig. 10, which will cause the bucket to tilt downwardly until it rests on both 20 of the supports 61 to cause it to extend under the outer end of the apron 27, the shafts 57 moving upwardly in the slotted bearings 62. In the raising movement of the bucket 25 47, the latter is first lifted from the support 61 at the right-hand side of Fig. 10, thus withdrawing the edge of the bucket from beneath its coöperating apron 27, continued upward movement of the bail 55 lifting the bucket entirely clear of the supports 61 and 30 causing it to be supported on the bail 55 as represented by dotted lines in Fig. 10.

Where it is desired to use the loader-mechanism described in connection with a single bucket instead of a pair thereof, and 35 operate the loader-mechanism to return it to normal filling position (Fig. 4) by the descent of a body, the cable 47^a, through the medium of which the bucket to be charged from the loader-mechanism is operated, may 40 be provided, at its opposite end, with a counterweight, instead of a bucket, which, in the operation of the hoisting-mechanism, hereinbefore referred to, would move in opposite directions to those of the bucket, as described 45 of the pair of buckets in the construction illustrated, and would engage with a cross-bar 48, which, in such case, would be directly connected with the end of the cable 52 opposite that to which the lever-mechanism 50 of the loader employed would be connected. Thus, the single loader-mechanism would be moved to discharging position upon the lowering of the bucket 47 coöperating therewith and would be returned to 55 normal filling position by the descent of the counterweight and during the rise of the bucket.

While I have illustrated and described the preferred form of my invention as embodied 60 in an apparatus, the hopper of which has its discharge-openings in opposed walls for drawing the coal from opposite sides of the hopper, it will be understood that the discharge-openings may be on the same side of 65 the hopper and that the loader-mechanisms

for discharging the coal into the buckets, where a plurality are employed, may be located side by side where such an arrangement is desired, without departing from the spirit of my invention. Furthermore, various changes and alterations may be made in the construction illustrated without departing from the spirit of my invention. 70

What I claim as new, and desire to secure by Letters Patent, is—

1. In apparatus of the character described, the combination with a hopper provided with a discharge-opening, of means for controlling the discharge of material from the apparatus comprising a measuring device 80 consisting of a chute communicating with said hopper-outlet, a door at the discharge-end of said chute, an under-cut gate in said chute extending at all times above the bottom of said chute and leaving a passage 85 way from the hopper to the door when the gate is open and operating to control the flow of material from the hopper to the chute, and elevating means for controlling the operation of said gate and door. 90

2. In apparatus of the character described, the combination with a hopper provided with a discharge-opening, of means for controlling the discharge of material from the apparatus comprising a measuring device 95 consisting of a chute communicating with said hopper-outlet, a door at the discharge-end of said chute, an under-cut gate in said chute separate from said door and extending at all times above the bottom of said 100 chute and operating to control the flow of material from the hopper to the chute, and means operatively connecting said gate and door together to cause said gate to be open when said door is closed, and said door to 105 be open when said gate is closed, elevating mechanism located adjacent to said first-named means for receiving material from said hopper, and means actuated by said elevating mechanism for actuating said 110 first-named means.

3. In apparatus of the character described, the combination with a hopper provided with a discharge-opening, of means for controlling the discharge of material from the apparatus comprising a measuring device 115 consisting of a chute communicating with said hopper-outlet, a door at the discharge-end of said chute, a pivotally mounted under-cut gate in said chute separate from said 120 door and extending at all times above the bottom of said chute and operating to control the flow of material from said hopper to said chute, and means operatively connecting together said gate and door to cause 125 said gate to be open when said door is closed, and said door to be open when said gate is closed, elevating mechanism located adjacent to said first-named means for receiving material from said hopper, and 130

means actuated by said elevating mechanism for actuating said first-named means.

4. In apparatus of the character set forth, the combination with a hopper provided with a discharge-outlet, of means for controlling the flow of material from said hopper comprising a measuring device consisting of a chute communicating with said hopper-outlet, a door at the discharge end of said chute, a pivotally supported undercut gate in said chute, said gate being at all times spaced from the bottom of said chute, and means operatively connecting said gate and door together to cause said gate to be open when said door is closed, and said door to be open when said gate is closed, elevating mechanism located adjacent to said first-named means for receiving material from said hopper, and means actuated by said elevating mechanism for actuating said first-named means.

5. In apparatus of the character set forth, the combination with a hopper provided with a discharge-outlet, of means for controlling the discharge of material from said hopper comprising a chute communicating with said hopper-outlet, a pivoted gate for said hopper-outlet constructed and arranged to permit material to flow from said hopper into the chute when the gate is open, a pivoted door for said chute beyond said gate, and means operatively connecting together said gate and door and operating when actuated in one direction to simultaneously open said door and close said gate, and close said door and open said gate when moved in the opposite direction, said last-named means being constructed and arranged to cause the initial rotary opening movement of said door and the initial rotary closing movement thereof to be slower and faster, respectively, than the rotary movement of said gate, and said door to be open when said gate is closed, elevating mechanism located adjacent to said first-named means for receiving material from said hopper, and means actuated by said elevating mechanism for actuating said first-named means.

50. 6. In apparatus of the character set forth, the combination with a hopper provided with a discharge-outlet, of means for controlling the discharge of the material from said hopper comprising a chute communicating with said hopper-outlet, a pivoted gate for said hopper-outlet constructed and arranged to permit material to flow from said hopper into the chute when the gate is open, a pivoted door for said chute beyond said gate, and lever-mechanism connected with said gate and door and operating when actuated in one direction to simultaneously open said door and close said gate, and close said door and open said gate when moved in the opposite direction, said last-named

lever-mechanism being constructed and arranged to cause the initial rotary opening movement of said door and the initial rotary closing movement thereof to be slower and faster, respectively, than the rotary movement of said gate while operating simultaneously with said door, elevating mechanism for receiving material from said hopper, and means for actuating said lever-mechanism from said elevating mechanism, for the purpose set forth.

7. In apparatus of the character set forth, the combination with a hopper provided with a discharge-outlet, of means for controlling the discharge of the material from said hopper comprising a chute communicating with said hopper-outlet, a pivotally-supported gate for controlling the flow of material from said hopper into said chute, a pivotally-supported door beyond said gate, and a link, extending both above and below the axis upon which said gate swings when said gate is open, operatively connecting said gate and door together to cause said gate to be open when said door is closed, and said door to be open when said gate is closed, said link extending closely adjacent to the axis upon which said gate swings when said gate is open and said door is closed, elevating mechanism for receiving material from said hopper, and means actuated by said elevating mechanism for actuating said first-named means, for the purpose set forth.

8. In apparatus of the character set forth, the combination with a hopper provided with a discharge-outlet, of means for controlling the discharge of the material from said hopper comprising a chute communicating with said hopper-outlet, a pivotally-supported gate for controlling the flow of material from said hopper into said chute, a pivotally-supported door for said chute beyond said gate, and a link, extending both above and below the axis upon which said gate swings when said gate is open, connecting said gate and door together to cause said gate to be open when said door is closed, and said door to be open when said gate is closed, said link extending closely adjacent to the axis upon which said gate swings when said gate is open and said door is closed, said link being connected with said door at a distance from the axis upon which the latter swings less than the distance from said gate to the axis about which the latter turns, elevating mechanism for receiving material from said hopper, and means actuated by said elevating mechanism for actuating said first-named means.

9. In apparatus of the character set forth, the combination with a hopper provided with a discharge-outlet, of means for controlling the discharge of material from said hopper comprising a chute communicating with said hopper-outlet, a gate for control-

- ling said hopper-outlet, a pivotally-supported door for said chute beyond said gate, lever-mechanism connected with said gate and door and operating when actuated in opposite directions to actuate said gate and door to alternately fill said chute and discharge the material therefrom, elevating mechanism for receiving material from said hopper, and means operatively connected with said lever-mechanism and actuated by said elevating mechanism, for operating said lever-mechanism in opposite directions, the connection between said lever-mechanism and said door being constructed and arranged to permit 15 said door to be raised without actuating said lever-mechanism, for the purpose set forth.
10. In apparatus of the character set forth, the combination with a hopper provided with a discharge-outlet, of means for controlling the discharge of material from 20 said hopper comprising a chute communicating with said hopper-outlet, a gate for controlling said hopper-outlet, a pivotally-supported door for said chute beyond said gate, lever-mechanism connected with said gate and door and operating when actuated in opposite directions to actuate said gate and door to alternately fill said chute and discharge the material therefrom, elevating 25 mechanism for receiving material from said hopper, and means actuated by said elevating mechanism for operating said lever-mechanism in opposite directions, said lever-mechanism including a break-joint connection between the connection of said lever-mechanism with said door and the connection of said lever-actuated means with 30 said lever-mechanism.
11. In apparatus of the character set forth, the combination with a hopper provided with a discharge-outlet, of means for controlling the discharge of material from 40 said hopper comprising a chute communicating with said hopper-outlet, a gate for controlling said hopper-outlet, a pivotally-supported door for said chute beyond said gate, lever-mechanism connected with said gate and door and operating when actuated in opposite directions to actuate said gate and 45 door to alternately fill said chute and discharge the material therefrom, elevating mechanism for receiving material from said hopper, and means actuated by said elevating mechanism for operating said lever-mechanism in opposite directions, the lever-mechanism between said gate and door being formed with a pair of pivotally-connected links one of which contains a slot and a stop and the other of which contains 50 a pin extending into said slot, said pin-equipped link being provided with a shoulder for releasably engaging said stop, for the purpose set forth.
12. In apparatus of the character described, 55 the combination with a hopper provided with a discharge-outlet, of means for controlling the discharge of material from said hopper including a gate and a door, and means operatively connecting said gate and door together and operating, when actuated, to alternately open said gate and close said door and close said gate and open said door, and a hoisting bucket and a body connected together for simultaneous movement in opposite directions, said bucket being movable adjacent to said first-named means for receiving material from said hopper through said first-named means, means extending into the path of downward movement of said bucket for opening said door and closing 60 said gate to discharge material into said bucket, and means extending into the path of downward movement of said body for closing said door and opening said gate, for the purpose set forth.
13. In apparatus of the character described, the combination with a hopper provided with a discharge-outlet, of means for controlling the discharge of material from said hopper including a gate and a door, and lever-mechanism operatively connecting said gate and door together and operating, when actuated in opposite directions, to alternately open 65 said door and close said gate and close said door and open said gate, a hoisting-bucket and a body connected together for simultaneous movement in opposite directions, said hoisting-bucket being movable adjacent to said means for receiving material from said hopper through said means, means extending into the path of downward movement of said bucket for actuating said lever-mechanism in one direction to close said gate and open said door, and means extending into the path of downward movement of said body for actuating said lever-mechanism in the opposite direction to close said gate and open said door, for the purpose set forth.
14. In apparatus of the character described, the combination with a hopper provided with a discharge-outlet, of means for controlling the discharge of material from said hopper comprising a chute, a door for the outlet-end of said chute, a gate for controlling said hopper-outlet, said gate and door being movable relative to said chute, and means operatively connecting said gate and door together and operating, when actuated, to alternately open said gate and close said door and close said gate and open said door, a hoisting-bucket and a body connected together for simultaneous movement in opposite directions, said bucket being movable adjacent to said first-named means for receiving material from said hopper through said first-named means, means extending into the path of downward movement of said bucket for opening said door and closing said gate to discharge material into said bucket, and means extending into the path of downward 110 movement of said body for closing said door and opening said gate, for the purpose set forth.

movement of said body for closing said door and opening said gate, for the purpose set forth.

15. In apparatus of the character described, the combination with a hopper provided with a discharge-outlet, of means for controlling the discharge of material from said hopper comprising a chute, a door at the discharge-end of said chute, a gate for controlling said hopper-outlet, said gate and door being movable relative to said chute, and lever-mechanism operatively connecting said gate and door together and operating, when actuated in opposite directions, to alternately open said door and close said gate and close said door and open said gate, a hoisting-bucket and a body connected together for simultaneous movement in opposite directions, said hoisting-bucket being movable adjacent to said means for receiving material from said hopper through said means, means extending into the path of downward movement of said bucket for actuating said lever-mechanism in one direction to close said gate and open said door to discharge material into said bucket, and means extending into the path of downward movement of said body for actuating said lever-mechanism in the opposite direction to close said door and open said gate, for the purpose set forth.

16. In apparatus of the character set forth, the combination of a hopper provided with a discharge-opening, of means for controlling the discharge of material from said hopper, comprising a chute, a door for the discharge-end of said chute, a gate for controlling said hopper-outlet, said gate and door being movable relative to said chute, means connecting said gate and door together and operating, when actuated, to open said door and close said gate and close said door and open said gate alternately, and a lever operatively connected with said gate and operating to actuate the latter and said second-named means, said lever extending intermediate the connections of said second-named means with said gate and door, a hoisting-bucket movable adjacent to said first-named means, and means connected with said lever and extending into the path of downward movement of said bucket, for the purpose set forth.

17. In apparatus of the character set forth, the combination with a hopper provided with a discharge-outlet, of means for controlling the flow of material from the apparatus comprising a measuring device consisting of a chute communicating with said hopper-outlet and having the upper end of its bottom curved upwardly, a door at the discharge-end of said chute, and a pivotally supported under-cut gate in said chute adjacent to the curved section of the latter, said gate being spaced from said curved section and constructed and arranged to cause the material from the hopper to flow into

said chute to said door when said gate is opened, elevating means for receiving material from said hopper, and means actuated by said elevating mechanism for operating said gate and door to alternately open said door and close said gate, and close said door and open said gate.

18. In apparatus of the character set forth, the combination with a hopper provided with a discharge-outlet, of means for controlling the flow of material from the apparatus comprising a measuring device consisting of a chute communicating with said hopper-outlet, a door at the discharge-end of said chute, and a pivotally-supported under-cut gate in said chute and spaced from the bottom of the latter when said gate is open, the space between said gate and chute being of greater cross-sectional area at its front end and becoming restricted toward its rear end, said gate being constructed and arranged to cause the material from the hopper to flow into said chute to said door when said gate is opened, elevating means for receiving material from said hopper, and means actuated by said elevating mechanism for operating said gate and door to alternately open said door and close said gate, and close said door and open said gate.

19. In apparatus of the character set forth, the combination with a hopper provided with a discharge-outlet, of means for controlling the flow of material from the apparatus comprising a measuring device consisting of a chute communicating with said hopper-outlet and having its bottom formed of a curved upper section, a door at the discharge-end of said chute, and a curved pivotally-supported under-cut gate in said chute adjacent to said curved chute-section and spaced therefrom, said gate being constructed and arranged to cause the material from the hopper to flow into said chute to said door when said gate is opened, elevating means for receiving material from said hopper, and means actuated by said elevating mechanism for operating said gate and door to alternately open said door and close said gate, and close said door and open said gate.

20. In apparatus of the character set forth, the combination with a hopper provided with a discharge-outlet, of means for controlling the flow of material from the apparatus comprising a measuring device consisting of a chute communicating with said hopper-outlet, a door at the discharge-end of said chute, and a pivotally-supported under-cut gate in said chute and spaced relative to the bottom of the latter when the gate is open to cause the coal-filling space in the chute to progressively increase as said gate is raised to shut off the flow of material into the chute, said gate being constructed and arranged to cause the material from the hopper to flow into said chute to said door when

said gate is opened, elevating mechanism for receiving material from said hopper, and means actuated by said elevating mechanism for actuating said first-named means.

- 5 21. In apparatus of the character set forth; the combination with a hopper provided with a discharge-outlet, of means for controlling the discharge of material from the apparatus comprising a measuring device consisting of a chute communicating with said hopper-outlet, a pivotally-supported under-cut gate in said chute for controlling the flow of material from said hopper into said chute, the lower end of said 10 gate extending into a position in which the material in the chute lies upon it, a pivotally-supported door for said chute beyond said gate, said gate being constructed and arranged to cause the material from the hopper to flow into said chute to said door when said gate is opened, and means connecting said gate and door together for causing said door to be closed when said gate is open, and through the medium of which said gate and 15 door are alternately operated to close said gate and open said door, and open said gate and close said door, elevating mechanism for receiving material from said hopper, and means actuated by said elevating mechanism for actuating said first-named means.

- 20 22. In apparatus of the character set forth, the combination with a hopper provided with a discharge-outlet, of means for controlling the discharge of material from

35 said hopper comprising a chute communicating with said hopper-outlet, a gate for controlling said hopper-outlet, a pivotally-supported door for said chute beyond said gate, link-mechanism connecting said gate and door together eccentrically of their pivots, 40 said link-mechanism including a break-joint connection between said gate and door, and means operating to break said joint before said door reaches the limit of its opening movement, and elevating mechanism for receiving material from said hopper through said chute, for the purpose set forth.

45 23. In apparatus of the character set forth, the combination with a hopper provided with a discharge-outlet, of means for controlling the discharge of material from said hopper comprising a chute communicating with said hopper-outlet, a gate for controlling said hopper-outlet, a pivotally-supported door for said chute beyond said gate, 50 link-mechanism connecting said gate and door together eccentrically of their pivots, said link-mechanism including a break-joint connection between said gate and door, and means on said door operating to break said joint before said door reaches the limit of its downward opening movement, and elevating mechanism for receiving material from said hopper through said chute.

55 ROBERT A. OGLE.
